US00D531871S

(12) **United States Design Patent** (10) **Patent No.:** **US D531,871 S**
Etter et al. (45) **Date of Patent:** **** Nov. 14, 2006**

(54) **ROUTER**

(75) Inventors: **Mark A. Etter**, Humboldt, TN (US);
Ginger L. Allen, Jackson, TN (US);
John M. Woodlief, Jackson, TN (US)

(73) Assignee: **Black & Decker Inc.**, Newark, DE (US)

(**) Term: **14 Years**

(21) Appl. No.: **29/232,207**

(22) Filed: **Jun. 16, 2005**

(51) LOC (8) Cl. **08-01**

(52) U.S. Cl. **D8/67**

(58) Field of Classification Search D8/61,
D8/67, 70, 107; 409/182, 180, 134, 132,
409/131; 144/48.6, 252.1, 154.5, 136.95

See application file for complete search history.

(57) **CLAIM**

We claim the ornamental design for a router, as shown.

DESCRIPTION

FIG. 1 is a front perspective view showing our new design;
FIG. 2 is a top plan view thereof;
FIG. 3 is a front elevation view thereof;
FIG. 4 is a left side elevation view thereof;
FIG. 5 is a rear elevation view thereof;
FIG. 6 is a right side elevation view thereof; and,
FIG. 7 is a bottom plan view thereof.
